United States Patent Office.

ANTHONY ISKE, OF LANCASTER, PENNSYLVANIA, ASSIGNOR TO HIMSELF
AND BENJAMIN MISHLER, OF SAME PLACE.

Letters Patent No. 77,193, dated April 28, 1868.

IMPROVED HOSPITAL-BEDSTEAD.

The Schedule referred to in these Letters Patent and making part of the same.

TO ALL WHOM IT MAY CONCERN:

Be it known that I, ANTHONY ISKE, of the city of Lancaster, in the State of Pennsylvania, have invented a new and useful Improvement on the Hospital-Bedstead, Patent No. 49,412, dated the 15th day of August, 1865; and I do hereby declare that the following is a full, clear, and exact description of the construction and operation of the same, reference being had to the accompanying drawings, making a part of this specification, in which—

Figure 1 is a perspective view of the bedstead, with my improvements in place.

Figure 2, a side elevation on a reduced scale, with the foot-section let down, &c.

Figure 3, a perspective view of the mattress.

Figure 4, an end elevation with the trap down.

Figure 5, a perspective view of the trap seen from beneath.

The nature of my invention consists in providing a means to enable an invalid to be relieved from the calls of nature without exertion on his part, and with ease to the attendant, and to facilitate the regulating or raising and lowering of the patient's head and shoulders, and other minor additions and changes.

The bedstead being made from light castings and wrought iron, differs in the general character of the previous form, and is made in three distinct sections, sections I, II, III. Section I forms the head. This, like section III, the foot part, is hinged at the corners or inner ends of the vertical side bars B G, to the flat or horizontal side bars, A, of the body or centre section II, by bolts or pins p. To section I and section III are hinged the slightly-curved rack-bars D K, so that both or either section can be adjusted to a slope of any desired angle. The teeth of the several rack-bars engage upon the foot cross-rods I. There is also a pivot-brace and attaching-pin, o, to stiffen the foot-section III. The central section II has also end-braces U. Each section is bound by cross-slats independently, as shown by c b, a h, and g H. There is a trap, L, with hooks l hung in loops under the central section II. This trap, fig. 5, has a lever-arm, J, on its lower side, movable on a pivot, j, and on its upper face is a raised oblong or oval cushion, made to match and fit into an opening, T, in the mattress, fig. 3. This lever-arm J extends beyond the side of the bedstead, and when the cushion P is in place. This arm is supported on a hook, R, attached to the upper hinge-bar A on one side. I also provide a support or sliding table, Q, for a vessel, Z. This table has grooves q, to set over the cross-rods I, on which it is made to slide, to carry the vessel back or forth. There is also a sunken portion on the table to receive the vessel, and a check-ring, i, on the cross-bars I, so that it is only necessary to release the lever-handle J, and turn it back. This will withdraw the plug or cushion P, and the trap will swing down. By sliding the table Q back against the stop, the vessel is duly adjusted to the opening in the mattress. A cord may be attached to the end of the lever J, and the other end to the foot-brace on the side, by which the lever can again be drawn back and slid into the hook-support, thus closing the opening in the mattress.

Without a minute detail, it will suffice to say that the present arrangement is highly approved of in several hospitals to which samples have been given on trial, and it is declared to possess all the facilities that could be desired. The changes introduced, and improvements made, consist in forming the bed in three distinct sections, the rack-bar adjustment, the introduction of the trap, sliding table, and open mattress, made in three sections to match the bedstead.

I am aware that bedsteads for invalids, made in three sections, are not new, nor means for raising the head-board and relieving the necessity of the patient. I am also aware of a semicircular rack-bar, actuated by means of a lever and pulley, as also the use of a windlass. Such are shown in the Patents, Nos. 41,526, 41,996, 44,399, 45,151, &c. Such arrangements I do not claim. But I am not aware that a trap swinging on hooks, with a lever and cushion, arranged in the manner specified, was ever known or used, nor flat side rails A, the ends fashioned into a loop for the perforations in the vertical side bars for a pin to form the hinge. The rack-bars

differ in swinging on a pivot, and acting by their own gravity when raising the head-section from one notch to the other. The enlarged base or knobs to the bedstead-posts are intended for casters, if desired.

What I claim as my invention, and desire to secure by Letters Patent, is—

In combination with my swinging trap L, I claim the sliding table Q, with its grooves q, supported on the cross-braces I, with the stop i, together with the arrangement of the several rack-bars D K, when held in pivots, and mode of making and connecting the several segments, all arranged and operating in the manner and for the purpose specified and shown.
